United States Patent Office

Des. 207,934
Patented June 13, 1967

207,934

DISPLAY STAND

Joseph Kovacik and William Mooney, New York, N.Y.
(both 1/2 Wide Range Industries Inc., 1300 Viele Ave., Bronx, N.Y. 10474)

Filed Aug. 5, 1966, Ser. No. 3,362

Term of patent 14 years

(Cl. D80—10)

FIG. 4.

FIG. 5.

FIG. 1 is a front elevational view of a display stand showing our new design;

FIG. 2 is a fragmentary side elevational view of the top portion thereof;

FIG. 3 is a fragmentary side elevational view of the base portion thereof;

FIG. 4 is a top plan view thereof; and

FIG. 5 is a bottom plan view thereof.

We claim:

The ornamental design for a display stand, as shown.
